UNITED STATES PATENT OFFICE.

CYRENUS WHEELER, JR., OF AUBURN, NEW YORK; DEXTER WHEELER, LUCY M. WHEELER, HARRIET T. WHEELER, AND CHARLES B. WHEELER EXECUTORS OF SAID CYRENUS WHEELER, JR., DECEASED.

COMBINED WASHBENCH AND CLOTHES-WRINGER.

SPECIFICATION forming part of Letters Patent No. 634,710, dated October 10, 1899.

Application filed November 20, 1897. Serial No. 659,276. (No model.)

To all whom it may concern:

Be it known that I, CYRENUS WHEELER, Jr., a citizen of the United States, residing at Auburn, in the county of Cayuga and State of New York, have invented new and useful Improvements in a Combined Washbench and Clothes-Wringer, of which the following is a specification.

My invention relates to reversible clothes-wringers as applied to folding washbenches; and it consists in so applying the wringer to the washbenches that it can be removed to permit folding and horizontally reversed to allow the operator to stand on either side of the bench when using it, thus enabling him or her to use the right hand at all times in turning the crank and the left hand to feed the clothing or fabric to the rolls. The wringer shown in the drawings is applied to washbenches that are arranged to hold two washtubs, and the operator can wring from either of the tubs to the other or from either tub to a basket, and when the work is finished the wringer can be removed from the benches and the benches folded so as to occupy but little space. I attain these results by the combination of devices illustrated by the accompanying drawings on two sheets, in which—

Figure 1, Sheet 1, is a plan view of the frame-work of the benches with the devices for supporting, reversing, and locking the wringer. Fig. 2 is a side elevation of Fig. 1, showing the wringer in working position by full lines and in its reversed working position by dotted lines. Fig. 3, Sheet 2, is a plan view of the top cross-piece 2, with the supporting-piece and locking devices and the wringer in place in full lines and as reversed in dotted lines. Fig. 4 is a side or edge view of supporting-piece 14. Fig. 5 is a sectional view through the center of the supporting-piece 14 and top cross-piece 2. Fig. 6 is an end view of Fig. 3 and a semisectional view of the latch-piece 16, pivoted to top cross-piece 2. Fig. 7 is a view of the opposite end of top cross-piece 2 with the double latch-piece in position.

The same numbers indicate like parts in all the figures.

11 are vertical standards for supporting the

inner ends of the tub-platforms of the wash-benches and the wringer. To the bottoms of these standards foot-pieces 33 are attached to afford a wide bearing upon the floor, and a cross-piece 13 connects the foot-pieces together, and on top of the standards is firmly fastened the top cross-piece 2. These standards are far enough apart to allow a tub placed on each platform to meet under the top cross-piece. The tub-platforms are made in two separate frames. The side pieces of one of them is shown by 44 and its legs by 55, which are hinged on the rounded ends of cross-piece 6 inside of the side pieces 44. The cross-piece 9 connects the opposite ends of the side pieces together, and on the top of 60 these cross-pieces is fastened the piece 8 to serve as a support for a smaller receptacle than an ordinary tub. The legs 55 have a cross-piece 12 to hold them at the same distance apart as their pivoted ends, and to the under 70 side of the side pieces 44 a cross-piece 7 is attached, which serves as a stop to prevent the legs from spreading too far outward. This tub-platform, as described, is pivoted by the inner ends of its side pieces 44 to the inside 75 of the standards 11 by the bolts 1111, which pass through the links 10, side pieces 44, and standards 11, thus permitting this bench to be turned upward on these bolts to fold it, as indicated by the arrow A, the legs 55 folding 80 downward on the round part of the cross-piece 6, as indicated by the arrow B. Another platform of like construction is pivoted to the other edge of the standards 11 by bolts 11' 11', so as to fold in like manner, as indicated by A' B'. In order to use lighter side pieces than otherwise could be done, a bearing-piece or rest 30 is firmly attached to the inside of the standards 11 by bolts 31, with its edge against the under side of the side 90 pieces 44 and 4' 4' and projects several inches past the edges of the standards. These bearing-pieces not only relieve the pivot-bolts by which the platforms are pivoted from the weight of the tub and contents, but serve as 95 braces to hold the standards at right angles to the tub-platforms and add stiffness to the whole framework.

The tub-platforms when folded can be securely held in place by connecting the hook 16 to the eye 17.

The clothes-wringer shown in the drawings 5 is of the U-spring type; but other types of wringers can readily be applied to the bench by the devices shown in the drawings, as I have used several different ones on the benches shown and described.

10 In applying the wringer to the benches a flanged socket-piece 24 is fastened centrally in the top cross-piece 2, which is high enough above the tub-platforms to allow the tubs to be placed under it and against each other.

15 A supporting-piece 14 is provided for supporting the wringer to which it is attached back of the rollers and is connected with the vertical pivot 23 by a web-piece 32 and a circular plate 22. This connecting-web is inclined 20 backward and downward from the supporting-piece 14 to the circular plate 22, which is united to the top of the pivot 23, which has its seat in the socket-piece 24, which is centrally located in the top cross-piece 2, the pivot being free to turn therein. The circular plate, 25 which is flat, will be on a lower plane than the supporting-piece 14, so as to bring the wringer high enough above the top cross-piece 2 to afford space for the locking devices.

30 This supporting-piece 14 is bolted to the under side of the U-springs of the wringer 18 in place of the ordinary tub-clamps and cross-bar by bolts 19. The wringer is now supported on the top cross-piece 2 by placing its pivot 23 in 35 the hole of the socket-piece 24, in which it will be free to turn horizontally in any direction. When in use, it is necessary to have the wringer held in a fixed position both vertically and horizontally, and in this one so that it can be

40 reversed at the pleasure of the operator or removed entirely from the benches. The locking devices will now be described. In each end of the supporting-piece 14 is a slot 21, formed at right angles to the pivot 23. The locking

45 or latch piece 15 is double and is fastened firmly to one end of the top of cross-piece 2 in a vertical line with the slot 21 when the wringer is swung into locking position with it, its ends 25 being in the same horizontal 50 plane as the slot and of the proper thickness to enter the slot when the wringer is turned on its pivot from one side to the other and are shouldered so as to stop the supporting-piece 14 in the proper position for operating

55 the wringer from either side of the benches. To the other end of the cross-piece 2 is fastened the swinging latch or locking piece 16, which has a circular foot-piece 29 pivoted to a base-plate 28, on which it is free to turn, 60 the base-plate being fastened on the cross-piece. The locking end of the latch is made

longer than the slot 21 and is curved downward to form a handle 26, by which to turn it in locking and unlocking it with the slot 21. By locating the pivot 23 back of the rolls it will be seen that in either of the positions in which the wringer-supports can be locked for use the rolls will stand far enough over the tub from which the wringing is being done to allow the water to fall into the tub.

The arrow C indicates the direction in which the wringer moves in changing it from its position as shown in full lines to that shown in dotted lines.

When the benches are to be folded, by turning the latch 16 out of slot 21 a partial turn of the wringer will release it from its connection with locking-piece 15, and it can be removed from its socket-piece in the top cross-piece of the washbenches.

Having described my invention, what I claim as new, and desire to secure by Letters Patent, is—

1. In combination with two washbenches composed of two tub-platforms, which have supporting-legs pivoted to their outer ends, their inner ends being pivoted to a central supporting-frame so as to permit their being folded upward against and carried by it; a clothes-wringer pivoted to the top cross-piece 90 of said supporting-frame so as to allow it to be reversed; a locking mechanism composed of a fixed double latch-piece at one end of the top cross-piece, and a single pivoted latch-piece at the other end adapted to lock with the horizontally-slotted ends of the supporting-piece, and hold it firmly in each of its working positions, substantially as described and shown.

2. The combination of two washbenches, 100 composed of two tub-platforms having supporting-legs pivoted to their outer ends, their inner ends being pivoted to the inner sides of a central vertical supporting-frame which will permit a tub on each platform to meet 105 together under the top cross-piece of the supporting-frame; the clothes-wringer having a supporting-piece provided with a web-piece that projects backward and inclines downward, and is united to a downwardly-projecting pivot, which is centrally located in the top cross-piece of the supporting-frame, and the bearing-pieces 30, attached to the standards 1, 1, to stiffen the side pieces of the platforms, and hold the supporting-frame vertical, when the wringer is in use, substantially 110 as described and shown.
